UNITED STATES PATENT OFFICE.

JOHN H. GALAWAY, OF NEW YORK, N. Y.

DESIGN FOR SPOON AND FORK HANDLES.

Specification forming part of Design No. 7,361, dated April 7, 1874; application filed March 14, 1874.
[Term of Patent 7 years]

To all whom it may concern:

Be it known that I, JOHN H. GALAWAY, of the city, county, and State of New York, have invented a new and original Design for Spoon and Fork Handles; and I do hereby declare the following to be a full, clear, and exact description thereof, which will enable those skilled in the art to make the same, reference being had to the accompanying drawings forming part of this specification, in which drawings—

Figure 1 represents a face view of a spoon-handle ornamented and formed according to my design. Fig. 2 is a rear view of the same.

Similar letters indicate corresponding parts.

In the drawing, the letter A designates the handle of a spoon or fork, said handle being composed of two principal sections, viz., the finger-piece a and the shank b. Said finger-piece joins the shank by converging curves c, and its outer end is flaring and provided with corners d, between which is situated an arabesque, e. A flat bead, f, extends along the edge of the finger-piece, both sides of which are ornamented alike, as shown in Figs. 1 and 2. The shank b appears to overlap the inner end of the finger-piece by a flange, g, which is

ornamented, as shown, and flat beads h extend along both edges of said shank and round the flange g. Between these beads is formed, on the upper side of the shank, a ridge, i, which terminates, at its junction with the bowl B, in an arabesque, j. On the under side of the shank is formed a depression, k, in place of the ridge i, and the beads h^a on the edges of the shank terminate in scrolls l and leaves m.

What I claim as new, and desire to secure by Letters Patent, is—

1. The design of the finger-piece a, with curves c, corners d, bead f, and arabesque e, as shown and described.

2. The design of the shank b, with its pointed flanges g, flat beads h, ridge i, and depression k, as shown and described.

3. The design for a spoon or fork handle composed of a finger-piece, a, and shank b, both being ornamented as shown and described.

JOHN H. GALAWAY.
